[57] CLAIM

The ornamental design for a bottle, as shown and described.

DESCRIPTION

FIG. 1 is a front elevational view of a bottle showing my new design;

FIG. 2 is a left side elevational view thereof;

FIG. 3 is a right side elevational view thereof;

FIG. 4 is a top plan view thereof;

FIG. 5 is a front elevational view of a bottle showing a second embodiment of the bottle illustrated in FIG. 1;

FIG. 6 is a left side elevational view thereof;

FIG. 7 is a right side elevational view thereof; and,

FIG. 8 is a top plan view thereof.

The undisclosed bottom portions of both embodiments are plane and unornamented.

FIG. 3

FIG. 2

FIG. 1
